HUBBARD N. JOSLEYN, OF SYRACUSE, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

945,956.

Specification of Letters Patent. Patented Jan. 11, 1910.

Application filed September 20, 1906. Serial No. 335,430.

To all whom it may concern:

Be it known that I, HUBBARD N. JOSLEYN, a citizen of the United States, and resident of Syracuse, in the county of Onondaga and 5 State of New York, have invented certain new and useful Improvements in Type-Writing Machines, of which the following is a specification.

My invention relates to clutches and especially to a clutch between the platen and the line space wheel of a typewriting machine for the purpose of effecting fractional line spacing.

My invention has for its principal object 10 to provide improved means whereby the platen of a typewriting machine may be turned to any desired position while the line space wheel is held fixed by its detent and whereby the platen may be positively 15 clutched to the line space wheel at any position to which said platen may be adjusted. In devices for this purpose it is important 20 that it be possible to adjust the platen to any desired position whatever, because an extremely slight displacement of some of the 25 letters out of line with the other letters is noticeable in typewriting. It is also very important that the platen and line space wheel be positively clutched together, as the line spacing lever is frequently operated 30 with considerable violence and there will be a slipping of the parts if any such slipping is possible. Devices in which the platen may be released from the line space wheel 35 so as to render said platen independently rotatable for fractional spacing and in which the two parts may be again secured together in adjusted position, have heretofore usually been of two general kinds: 40 namely, those in which the parts are connected by some form of friction device and those in which they are connected by some form of toothed clutch mechanism. The friction clutches permit of an adjustment of 45 the platen to any degree of fineness, but these clutches are open to a number of objections. It has been found extremely difficult to construct such clutches so that there will be no slipping when the line space lever 50 is violently operated and such clutches have usually comprised a stiff spring, the tension of which had to be overcome by hand when the clutch was disengaged. In those

clutches in which toothed members are employed it is possible to clutch the two members together positively, but in most of such devices it is not possible to secure the requisite fineness of adjustment. These devices are adapted to clutch the members together only in certain predetermined relative positions, in which the teeth of the clutch members are in register; and when the platen is adjusted to the precise position desired, it will be displaced to a greater or less extent when the clutch is thrown in unless this position happens to coincide with one of said predetermined positions, the extent of such displacement depending on the size of the clutch teeth. With these devices a certain degree of fineness of adjustment can be secured by making the teeth very small, but even with the smallest teeth that it is practicable to employ the displacement that is liable to occur when the clutch is thrown in is sufficient to be very objectionable.

The present invention embodies a toothed clutch mechanism and it is of such a character that the teeth may be of good size, and the platen may be positively clutched to the line space wheel in any position to which it may be adjusted. That is to say, no matter in what position the platen is set it will be positively clutched to the line space wheel without being displaced relatively to said line space wheel.

In the accompanying drawings, Figure 1 is a central longitudinal sectional view of the platen and line space wheel and some of the associated parts of a Monarch typewriter having one form of my invention applied thereto. Fig. 2 is a left-hand end view of the platen and line space wheel and some of the associated parts with the platen rod shown in section and some of the parts of the mechanism removed. Fig. 3 is a diagrammatic view similar to Fig. 2 but showing the parts in a different relation. Fig. 4 is a perspective view of the left-hand platen head. Fig. 5 is a view similar to the left-hand part of Fig. 1, but showing the platen unclutched from the line space wheel. Fig. 6 is a diagrammatic view of some of the parts shown in Fig. 2 but with the dogs in retracted or unclutched position. Fig. 7 is a perspective view of one of the clutching dogs. Figs. 8, 9 and 10 show another form of

the invention. Figs. 8 and 9 are fragmentary longitudinal sectional views through the left-hand end of the platen and some of the parts associated therewith, the clutch being shown 5 in normal position in Fig. 8 and in its released position in Fig. 9. Fig. 10 is a perspective view of one of the clutching dogs used in this form of the invention.

My invention is applicable to typewriting 10 machines generally but I have here shown it applied to that sort of typewriting machine in which the keys and printing instrumentalities are mounted in a stationary frame and in which the paper is passed about a 15 rotary platen. Some of the features shown in the drawings are those ordinarily employed in the Monarch typewriter. This machine has a paper carriage comprising two forwardly extending end pieces 1, in 20 which is mounted a roller platen 2. Said platen has a shaft 3 having a left-hand finger wheel 4 and a right-hand finger wheel 5 mounted on the ends thereof and secured to the shaft by set screws 6 threaded through 25 the hubs of the finger wheels and engaging the shaft. Just inside of each of said hubs there is a bearing sleeve 7 that loosely surrounds the shaft and that passes through the end piece 1 of the carriage where it is 30 secured in position by a set screw 8 threaded through said end piece from below and engaging the sleeve. The construction is such that the sleeves 7 are thus held rigid in the carriage and the shaft 3 is journaled in 35 them. The platen has a right-hand platen head 10 which is secured to the shaft 3 by a set screw 11 threaded through the hub of said platen head and which is secured to the platen by screws 12. In the Monarch ma- 40 chine the line space mechanism is at the left-hand end of the platen and said platen has a left-hand platen head 13, the former of which I have modified in order to adapt it to my clutch mechanism. The platen head 45 13 which is shown in detail in Fig. 4, is secured to the platen by screws 14 in the usual manner, said screws passing through countersunk openings 15. As is best shown in said Fig. 4, the outer face of the platen head 50 13 has projecting therefrom three annular ribs or three segments of an annular rib or flange 16, said segments being separated by three openings or slots 17 in which three clutching dogs 18, 19 and 20 are maintained 55 in such fashion that they are free to slide readily in and out in a direction toward and from the shaft 3, they being guided in such movements by the walls of the slots 17.

The line space wheel 22 is in the form of 60 a ring having an angular cross-section, as shown in Fig. 1, thus forming a flange, the left-hand face of which has the usual crown ratchet teeth 23 formed therein for co-operation with the line space pawl (not shown) 65 and with the detent roller 24 which is jour-

naled in the usual way in a spring arm 25 that is secured to the left-hand end piece 1 of the carriage. The detent roller 24, being pressed by the resiliency of the spring arm 25 toward the right, normally holds the line 70 space wheel in one or another of the line space positions in the usual way, but this roller prevents the line space wheel from occupying intermediate positions. The other flange of the line space wheel extends inward and has a series of internal teeth 26 formed on its inner surface, leaving notches or recesses between said teeth. The points or edges of these teeth bear on the periphery of the annular projection or projections 80 16 which thus form the bearing for the line space wheel. The faces of the teeth 26, or the sides of the notches or recesses between said teeth, constitute contact surfaces for co-operation with certain dogs or clutch de- 85 vices presently to be described. Where, in the claims, I use the word "tooth" or its derivatives, referring to the teeth 26, I mean such expressions to be construed broadly to 90 include any configuration of the parts re-sulting in contact or engaging surfaces having the function of the teeth 26 shown in the present instance. It may be possible to produce these contact or engaging surfaces without producing teeth which project like 95 those shown in the drawings; and I would regard such constructions as being the equivalents of that shown and described in the present case. The projections 16 are cut as 100 shown in Fig. 4 at 27 in order to permit of the insertion of the screws 14. The teeth 26 as seen from the face of the wheel, are pointed, both working faces of each tooth being at an inclination to the radius of the wheel and preferably at the same inclination to 105 said radius. As shown in the present instance these teeth have their opposite faces at an angle of about 60° with each other. I have found this to be a good angle for the 110 purposes of this form of the invention, but it may be varied to a considerable extent. Each of the dogs 18, 19 and 20 has its outer end formed into a tooth 28 adapted to enter the notches or recesses between the teeth 26, the two faces of the teeth 28 being inclined 115 to correspond with the inclination of the working faces of the teeth 26 so that if the platen happens to stand in the position shown in Fig. 3 for example, in which the tooth 28 of the dog 20 happens to extend to 120 the bottom of the notch between two of the teeth 26, the tooth 28 fits nicely in said notch.

The platen head 13 inside of the platen 2, has a part 30^a that fits snugly within the 125 core of the platen, and a cylindrical extension 30 in which are three holes 31 extending from the left-hand face of the platen head and terminating short of the right-hand end of the extension 30. In these holes 130

are seated three plungers 32, having springs 33 compressed between their right-hand ends and the bottoms of the holes 31. The left-hand end of each of these plungers is beveled, as shown in Fig. 1, at 34 to form a wedge or cam which contacts with the inner end of one of the dogs 18, 19 and 20, which inner ends of said dogs are formed at an inclination corresponding to that of the 5 wedge face 34. The construction is such that the springs 33 press the plungers 32 toward the left and the wedge or camming action of these plungers tends to press the dogs 18, 19 and 20 firmly into engagement 10 with the teeth 26 of the line space wheel. The inclination of the wedge 34 is so slight that even if very great pressure be exerted tending to move the dogs 18, 19 and 20 toward the shaft 3, such pressure would not 15 cause the plungers to be moved toward the right. The construction is such that when one of the dogs is thus wedged into engagement with one or both of the sides of a notch between two of the teeth 26, such engagement 20 is positive and cannot be released by pressure on the dog. When it is desired to uncouple or disengage the platen from the line space wheel all of the wedges 32 are pressed toward the right against the tension 25 of their springs 33 by a disk 35 slidably mounted on the shaft 3 just to the left of the left-hand ends of said wedges. The shaft 3 has a longitudinal slot 36 cut therein and a pin 37 projects from the disk 35 into 30 said slot. A push pin 38 lies loosely in the longitudinal slot 36 and extends out through the middle of the left-hand finger wheel 4, said push rod having a push button 40 mounted on its outer end. In order to bring 35 the outer end of the rod 38 into the axis of the shaft 3, said rod is off-set as shown at 40 and the slot is deepened near the end of the shaft, as shown at 42. The off-set 41 prevents the push rod 38 from being withdrawn 45 lengthwise from its seat. The construction is such that if the button 40 be pressed toward the right, the rod 38, acting on the pin 37, will push the disk 35 toward the right, pressing all of the wedges 32 back 50 to the position shown in Fig. 5.

I have provided means for withdrawing the dogs 18, 19 and 20 from the recesses or notches in the line space wheel when the button 40 is pushed in as described. In the 55 form of the invention shown in Figs. 1-7, each of said dogs has projecting from its left-hand face a pin 43 against which there presses the free end of a light spring 44 which is secured at its opposite end to the 60 flange 16 by a screw 45 and which presses against a stationary pin 46. When the wedges are withdrawn these springs 44 move the dogs toward the center of the platen and out of the way of the teeth 26, 65 the springs being merely of sufficient

strength to effect this result. When the parts are in this position the platen may be turned to any desired position by means of the finger wheels 4 and 5 without turning the line space wheel. 70

I have provided a cover 47 which is secured to the platen head 13 by screws 48 (Fig. 1) which pass through said cover and are threaded into openings 49 (Fig. 4) in the flanges 16. The cover 47 is recessed in 75 the middle to permit of the motion of the disk 35 and it also has an annular groove 50 formed in its right-hand face to accommodate the pins 43 and springs 44. The inner end of this cover is seated within the 80 flange of the line spacing wheel which carries the teeth 23 and forms a bearing therefor and also engages the inwardly projecting flange of the line space wheel and retains said wheel in position, preventing displacement of said wheel toward the left. Said cover also retains the dogs 18, 19 and 20 in position in their guide-slots and 85 protects the parts from dust and injury.

The parts are so designed that the angular 90 distance from the point of the tooth 28 of one dog to the point of the tooth of either of the others is not equal to the angular distance occupied by any whole number of the teeth 26. This relation may be secured in 95 any one of a number of ways. In the present instance I have shown fifty-seven teeth 26. This number fifty-seven is exactly divisible by three so that if the points of the teeth 28 of the dogs 18, 19 and 20 were uniformly spaced, that is to say, if they were spaced 120° apart, the relation above referred to would not obtain. As shown in the diagram in Fig. 6, the points of the teeth 28 of the dogs 19 and 20 are off-set from the 100 center lines of said dogs so that the distance from the point of the tooth 28 of the dog 18 to the point of the tooth 28 of either of the dogs 19 and 20 is equal to nineteen and one-fourth of the teeth 26 and the distance between the points of the teeth 28 of the dogs 105 19 and 20 is equal to eighteen and one-half of the teeth 26. When the parts are in the position shown in Fig. 2 the dog 18 is in full engagement with one of the notches between 110 two successive teeth 26, the dog 19 is in about one-half engagement with one side of one of said notches and the dog 20 in about one-half engagement with one side of one of said notches. It will be noted that in this particular position of the parts the dog 18 tends to hold the line space wheel from turning 115 relatively to the platen in either direction and if this dog had a sufficiently tight fit in its slot 17 it would alone be sufficient to 120 hold the wheel. It will be perceived that in this position of the parts the dog 19 will positively prevent rotation of the line spacing wheel relatively to the platen in the direction of the arrow in Fig. 2, and that the 125 130

dog 20 will positively prevent rotation of said line spacing wheel relatively to the platen in the opposite direction. The poorest engagement that can be effected between the parts is that shown in Fig. 3 in which a tooth of one of the dogs, say 20, is in full engagement with the notch between two teeth 26 and the other of these two dogs has the point of its tooth 28 at or near the top or point of one of the teeth 26. The dog 18 is in about one-half engagement with one side of one of the notches. In this position the dog 19 is inoperative, but the other two will hold the line spacing wheel against any rotation whatever relatively to the platen. Ordinarily the platen would not happen to be arrested relatively to its line spacing wheel in either of the two positions shown in Figs. 2 and 3 but in some intermediate position in which no one of the points of the teeth 28 would extend fully to the bottom of the notch between two of the teeth 26. No matter what relative rotative adjustment the parts may have there will always be at least one of the dogs that engages one side of one of the notches when the clutch is in operation and thus positively prevents rotation of the line spacing wheel independently of the platen in one direction and at least one other dog that engages the opposite side of another notch and thus prevents rotation of the line spacing wheel independently of the platen in the opposite direction. The line spacing wheel will thus always be positively locked against turning relatively to the platen in either direction and these two elements will therefore be rigidly and positively clutched together so that an actuation of the line spacing mechanism at this time will cause the line spacing wheel and platen to turn together.

It will be understood that the springs 33 do not need to be heavy springs but may on the contrary be rather light so that the force with which the dogs are pressed into the recesses between the teeth 26 is not sufficiently great to cause the platen to turn with relation to the line space wheel should one dog engage in advance of another, but when all of the dogs are pressed to operative position the wedges 32, 34 positively retain them in such positions so that they cannot be moved back toward the shaft 3 by any force applied at their outer ends.

It will be understood, of course, that the different wedges 32 will usually move different distances when the pressure of the finger or thumb on the button 40 is released. Thus when the parts stand in the position shown in Fig. 3, the dog 19 is nearly in its retracted position and the corresponding wedge 32 has therefore been permitted to move toward the left but a short distance. The dog 18 has moved farther from its retracted position and its wedge 32 has there-

fore moved farther toward the left. The dog 20 is in its extreme outer fully engaged position and the corresponding wedge must therefore have moved to its extreme left-hand position. If the button 40 be now 70 pushed in, the disk 35 will obviously first encounter the wedge 32 associated with the dog 20, next that associated with the dog 18 and last of all that associated with the dog 19. If the button be released without moving the platen the springs 33 will move the button toward the left. In this motion the wedge 32 associated with the dog 19 will obviously be arrested first, then the wedge 32 associated with the dog 18 will be arrested and last of all the wedge 32 associated with the dog 20.

In Figs. 8, 9 and 10 I have shown a form of my invention in which the springs 44 for retracting the dogs are dispensed with and are replaced by means for positively withdrawing the dogs from the teeth 26. In this form of the invention the annular groove 50 in the cover is not required and may be dispensed with. In said Figs. 8, 9 90 and 10, most of the parts that are common to the two forms of the invention are designated by reference characters similar to those used in the other figures. The form of the platen head 13 and the line space wheel 95 are the same as those already described. The three dogs 18^a, however, do not have the pins 43 but each of said dogs has projecting from its inner end toward the left a toe or cam 51 as shown in detail in Fig. 10, said cam being adapted to coöperate with the inner surface of an internally coned flange 52 formed on the pusher or disk 35^a. When said disk is pushed toward the right to the position shown in Fig. 9 the inclined conical surface of this flange engaging the inclined faces of the toes 51 positively cams the dogs toward the shaft 3, thus positively withdrawing them from engagement with the teeth 26. In this form of the invention each 100 of the plungers or wedges 32^a has a straight extension 53, the end of which is adapted to contact with the flat face 54 of the disk 35^a. When the rod 38 is pushed toward the right this flat face of the disk 35^a, acting on 110 the prolongations 53 of the wedges 32^a pushes said wedges toward the right and in the last part of the motion of the disk 35^a the coned face of the flange 52 engages the toes 51 and withdraws the dogs to their 115 inoperative positions.

The construction of the parts is such that the platen may be readily removed from the machine without disturbing the platen clutch. If it be desired to thus remove the 125 platen the set screw 6 of the left-hand finger wheel 4 is loosened and said finger wheel is removed. In this operation the push rod 38 will be withdrawn from its slot 36 and will remain associated with the finger wheel. 130

The set screw 11 of the right-hand platen head is next loosened and the shaft 3 is pulled out from the right, thus leaving the platen entirely free from the machine. 5 When the shaft is thus withdrawn the disk 35 is maintained in its proper position by the cover 47 in which it is inclosed. When it is desired to replace the platen on the machine the platen is set in position between the two sleeves 7 and the shaft is inserted 10 from the right passing freely through the platen head 10 and through the platen head 13 and its extension 30 and also through the disk 35. In inserting the shaft into the disk 35 it is, of course, essential that said shaft be turned until the slot 36 registers with the pin 37. When the shaft is set in place the set screw 11 is tightened, the rod 38 is inserted in its slot 36 and the finger wheel 40 15 properly positioned and secured in position by tightening the set screw 6.

Some of the features of the invention herein set forth are broadly new. As far as I am aware it is broadly new to provide a 20 plurality of dogs that are adapted to coöperate with a series of teeth in such fashion that when the clutch is in use, at least one of said dogs will always prevent relative motion of the two elements to be clutched together in one direction and at least one of 25 said dogs will always prevent relative motion of said elements in the other direction no matter in what relative positions the two parts may happen to be. It will, of course, be understood that more than three dogs 30 may be provided if desired, but three is enough to insure the mode of operation specified. The broad principle of this clutch is capable of embodiment in a great 35 variety of forms, some of them differing widely from either of the forms shown in the present case. I therefore do not regard my invention as limited to the precise form 40 of clutch shown in this case but wish to be understood as claiming the invention 45 broadly.

What I claim as new and desire to secure by Letters Patent, is:—

1. In a clutch device, the combination of 50 two elements to be clutched together, a series of teeth on one of said elements, a plurality of separately movable dogs on the other of said elements, and means for moving one of said dogs differentially to engage a tooth on 55 one side to positively prevent relative motion of said elements in one direction and for moving another of said dogs differentially to engage a tooth on the other side to positively prevent relative motion of said elements in 60 the other direction and for holding said dogs positively against displacement by any tendency to relative motion between said elements, each dog moving into engagement a 65 distance depending on the exact relative position of said elements, whereby said ele-

ments can be positively clutched together in any relative position thereof without being displaced by the clutch.

2. In a clutch device, the combination of 70 two elements to be clutched together, a series of teeth on one of said elements, and a plurality of separately movable dogs on the other of said elements, each of said dogs being adapted to engage either side of any one of said teeth, and the arrangement being 75 such that in any relative position of the two elements, at least one of said dogs will prevent relative motion of the two elements in one direction and at least one of said dogs will prevent relative motion of said elements 80 in the opposite direction, and wedges for holding said dogs in engagement with said teeth.

3. In a clutch device, the combination of 85 two elements to be clutched together, a series of teeth on one of said elements, three dogs on the other of said elements and each adapted to engage either side of any of said teeth, means operative in any relative position of 90 said elements for moving at least one of said dogs into engagement with one side only of one of said teeth to prevent relative motion of said elements in one direction and for moving another of said dogs into engagement with the other side only of one of said 95 teeth to prevent relative motion of said elements in the other direction and for holding said dogs positively against displacement by any tendency to relative motion between said elements, whereby said elements can be positively clutched together in any relative position thereof without displacement by the clutch.

4. In a clutch device, the combination of 100 two rotary elements to be clutched together, a circular series of teeth on one of said elements, a plurality of dogs on the other of said elements, and wedge means operative in any relative position of said elements to wedge each of said dogs into engagement 105 with said teeth without disturbing the relative position of the elements, the arrangement being such that in any relative position of said elements at least one of said dogs will positively prevent relative rotation of said 110 elements in one direction and at least one of said dogs will positively prevent relative rotation of said elements in the opposite direction.

5. In a clutch device, the combination of 115 two rotary elements to be clutched together, a series of teeth on one of said elements, three dogs, each adapted to engage either side of any one of said teeth, spring pressed cams for moving said dogs into engagement 120 with said teeth, the arrangement being such that in any relative position of said elements, at least one of said dogs will positively prevent relative rotation of said elements in one direction and at least one of 125 said elements in the opposite direction.

- said dogs will positively prevent relative rotation of said elements in the opposite direction, and means for releasing said dogs.
6. In a clutch device, the combination of two rotary elements to be clutched together, a series of teeth on one of said elements, each of said teeth having inclined faces, a plurality of dogs on the other of said elements, each of said dogs having two engaging faces inclined to correspond with the inclined faces of said teeth and each of said dogs being movable into and out of engagement with said teeth, and means operative in any relative position of said elements for moving each of said dogs into locking engagement with said teeth without disturbing the relative position of said elements and for holding the dogs positively against displacement by any tendency to relative motion between the elements, the arrangement being such that in any relative position of said elements at least one of said dogs will have one of its faces engaging one of the faces of one of said teeth to prevent relative motion of said elements in one direction, and at least one of said dogs will have one of its faces engaging one of the faces of one of said teeth to prevent relative motion of said elements in the opposite direction.
7. In a clutch device, the combination of two rotary elements to be clutched together, a series of internal teeth on one of said elements, each of said teeth having inclined faces, a plurality of dogs on the other of said elements, each of said dogs having two engaging faces inclined to correspond with the inclined faces of said teeth and each of said dogs being movable radially into and out of engagement with said teeth, the arrangement being such that in any relative position of said elements at least one of said dogs will have one of its faces engaging one of the faces of one of said teeth to prevent relative motion of said elements in one direction, and at least one of said dogs will have one of its faces engaging one of the faces of one of said teeth to prevent relative motion of said elements in the opposite direction, and spring pressed wedges, movable parallel to the axis of said rotary element for camming said dogs into engagement with said teeth.
8. In a typewriting machine, the combination with a platen and a line space wheel, one of which elements carries a series of teeth having inclined locking faces, of three dogs having inclined locking faces, means for moving said dogs into engagement with said teeth, the arrangement being such that in any relative position of said elements at least one of said dogs will engage one side or face of one of said teeth and at least one of said dogs will engage the other side or face of one of said teeth and in some relative adjustments of the parts any one of said dogs will be engaged on one of its faces and in other adjustments the same dog will be engaged on the other face, and means for releasing said dogs, whereby said platen is positively and releasably connected with said line space wheel by wedge action.
9. In a typewriting machine, the combination of a line space wheel having internal teeth, a platen having a platen head on which said line space wheel is mounted and relatively to which the platen and platen head may be turned, three dogs mounted in said platen head for radial motion into and out of engagement with said teeth and so disposed that in any position of said platen with relation to said line space wheel at least one of said dogs will be adapted to hold said platen against motion in one direction and at least one of said dogs will be adapted to hold said platen against motion in the other direction, wedges movable longitudinally of said platen and controlling said dogs, and means for moving said wedges.
10. In a typewriting machine, the combination of a line space wheel having internal teeth, a platen having a platen head on which said line space wheel is mounted and relatively to which the platen and platen head may be turned, three dogs mounted in said platen head for radial motion into and out of engagement with said teeth and so disposed that in any position of said platen with relation to said line space wheel at least one of said dogs will be adapted to hold said platen against motion in one direction relatively to the line space wheel and at least one of said dogs will be adapted to hold said platen against motion relatively to the line space wheel in the other direction, wedges movable longitudinally of said platen and controlling said dogs, springs for moving said wedges to locking position, and hand operated means for moving said wedges to inoperative position.
11. In a typewriting machine, the combination of a line space wheel having teeth, a platen having a platen head on which said line space wheel is mounted and relatively to which it is adapted to turn, a dog mounted in said platen head for motion into and out of engagement with said teeth, a spring pressed wedge independent of said dog and movable longitudinally of said platen and operating to force said dog into engagement with said teeth, a platen shaft, and a rod extending longitudinally of said shaft and adapted to move said wedge against the tension of its spring.
12. In a typewriting machine, the combination of a line space wheel having internal teeth, a platen having a platen head on which said line space wheel is mounted and relatively to which it may be turned, a plurality of locking dogs mounted in said

5 platen head for rectilinear radial motion into and out of engagement with said teeth, a platen shaft, a hand operated, longitudinally movable rod extending longitudinally 5 of said shaft, and means whereby said rod controls said dogs.

13. In a typewriting machine, the combination of a platen having a platen head and a shaft, a line space wheel relatively to 10 which the platen and platen head may be turned and having a series of teeth with inclined locking faces, three dogs mounted in said platen head and having locking faces inclined to correspond with the faces of said 15 teeth, means for moving said dogs into engagement with said teeth, the construction being such that said dogs hold said line space wheel engaged with the platen head and platen by wedge action and the dogs 20 being so arranged that in any relative position of said platen and line space wheel at least one of said dogs positively holds said platen against rotation relatively to said line space wheel in one direction and at 25 least one of said dogs positively holds said platen against rotation relatively to said line space wheel in the opposite direction, a hand operated rod extending longitudinally of said shaft, and means controlled by 30 said rod for releasing said dogs.

14. In a typewriting machine, the combination of a platen having a platen head and a shaft, a line space wheel adapted to turn with and to afford an independent rotation 35 of said platen and platen head and having a series of teeth with inclined locking faces, three dogs mounted in said platen head and having locking faces inclined to correspond with the faces of said teeth, means for moving 40 said dogs into engagement with said teeth, the construction being such that said dogs hold said line space wheel to the platen by wedge action and the dogs being so arranged that in any relative position of said 45 platen and line space wheel at least one of said dogs positively holds said platen against rotation relatively to said line space wheel in one direction and at least one of said dogs positively holds said platen 50 against rotation relatively to said line space wheel in the opposite direction, a hand operated rod extending longitudinally of said shaft, and a disk surrounding said shaft and controlled by said rod for releasing said 55 dogs.

15. In a typewriting machine, the combination of a platen having a platen head with a flange or projection on one face thereof, a line space wheel rotatably mounted on 60 said flange and having internal teeth, and locking dogs mounted in slots in said flange and adapted to lock said line space wheel and said platen together.

16. In a typewriting machine, the combination of a platen having a platen head with

a flange or projection on one face thereof, a line space wheel rotatably mounted on said flange and having internal teeth, locking dogs mounted in slots in said flange and adapted to lock said line space wheel and 70 said platen together, and wedges movable longitudinally of said platen and adapted to move said dogs into locking engagement with said teeth.

17. In a typewriting machine, the combination of a platen having a platen head with a flange or projection on one face thereof, a line space wheel rotatably mounted on said flange and having internal teeth, locking dogs mounted in slots in said flange and 80 adapted to lock said line space wheel and said platen together, and a cover secured to the face of said platen head and serving to retain said line space wheel in position on 85 said flange.

18. In a typewriting machine, the combination of a platen having a removable shaft, a line space wheel, a platen clutch connecting said line space wheel with said platen, means for releasing said platen clutch comprising 90 a rod lying in a groove in said shaft and a member surrounding said rod and having a pin extending into said groove, and means for retaining said member in position when said shaft is removed.

19. In a typewriting machine, the combination of a platen, a line space wheel, and a clutch for coupling said platen and line space wheel together, said clutch comprising a series of teeth, a dog adapted to coöperate 100 with said teeth, and means operative in any relative position of the line space wheel and platen and including a spring-pressed wedge or cam for moving said dog into contact with one or more of said teeth in the precise 105 position in which said teeth may happen to stand in any relative adjustment of the parts and without disturbing the relative position of said parts, the dog moving different distances depending on the relative adjustment 110 of the parts, and for holding said dog in the position to which it has been moved, said means holding the dog positively against displacement by any tendency to relative motion between the line space wheel and platen. 115

20. In a typewriting machine, the combination of a line spacing wheel, a platen adapted to rotate with and independently thereof, teeth carried by one of said parts, independently movable dogs coöoperating 120 with said teeth and carried by the other of said parts, and independently operable wedges coöoperating with said dogs, one for each dog.

21. In a typewriting machine, the combination of a platen, a line space wheel and a clutch for coupling these two elements together, said clutch comprising a series of teeth on one of said elements, a radially movable dog engaging said teeth, and a hand 125

operated clutch releasing device comprising a cam movable longitudinally of the platen for positively withdrawing said dog from engagement with said teeth.

- 5 22. In a typewriting machine, the combination of a platen, a line space wheel and a clutch for coupling these two elements together, said clutch comprising a series of teeth on one of said elements, a plurality of 10 radially movable dogs engaging said teeth, and a hand operated clutch releasing device comprising a cone-shaped cam movable longitudinally of said platen and adapted positively to withdraw said dogs from said 15 teeth.
23. In a typewriting machine, the combination of a platen, a line space wheel, a clutch for coupling these two elements together, said clutch comprising a series of 20 internal teeth on said line space wheel, a plurality of radially movable dogs engaging said teeth, and a hand operated releasing device comprising a member movable longitudinally of said platen and having an inter- 25 nally cone-shaped cam surface for withdrawing said dogs from said teeth.

24. In a typewriting machine, the combination of a platen, a line space wheel, a clutch for coupling these two elements together, said clutch comprising a series of internal teeth on said line space wheel, a plurality of radially movable dogs engaging said teeth, wedges movable longitudinally of the platen for pressing said dogs into engagement with said teeth, and a hand operated releasing device comprising a member movable longitudinally of said platen and adapted to withdraw said wedges, and means for withdrawing said dogs from said teeth.
- 40 25. In a typewriting machine, the combination of a platen, a line space wheel, a clutch for coupling these two elements together, said clutch comprising a series of internal teeth on said line space wheel, a plurality of radially movable dogs engaging said teeth, wedges movable longitudinally of the platen for pressing said dogs into en-

gagement with said teeth, and a hand operated releasing device comprising a member movable longitudinally of said platen and adapted to withdraw said wedges, said member having a cam portion for positively withdrawing said dogs from engagement with said teeth.

- 5 26. In a typewriting machine, the combination of a line spacing wheel, a platen adapted to rotate with and independently thereof, teeth carried by one of said parts, and independently movable dogs co-operating with said teeth and carried by the other 10 of said parts, independently operable spring pressed wedges co-operating with said dogs, one for each dog, whereby a simultaneous or successive engagement between said dogs and teeth may be effected through said independently operable wedges depending on the relations between the line spacing wheel and platen and whereby the line spacing wheel and platen may be positively locked together and maintained in any relative ad- 15 justment they may assume.

27. In a typewriting machine, the combination of a line spacing wheel, a platen adapted to turn with or independently of said line spacing wheel, and means for positively connecting the line spacing wheel and platen to turn together at any point or relative adjustment between the two, said means comprising a plurality of teeth connected with one of said parts and a plurality of independently movable teeth operatively connected with the other of said parts and adapted to positively engage said first mentioned teeth at different depths in the space between them depending on the precise relative adjustment of said parts.

Signed at Syracuse, in the county of Onondaga, and State of New York, this 18th day of September, A. D. 1906.

HUBBARD N. JOSLEYN.
